Application December 8, 1945, Serial No. 633,745
 In Switzerland January 13, 1945

6 Claims. (Cl. 230—209)

1

The present invention relates to a multi-stage compressor in which at least one impeller is provided with blades for working with high peripheral speeds and for obtaining high stage-pressure ratios. The invention consists in that the passage from one stage into the next is effected through a cooler, which is arranged within the compressor casing and forms an organic unit with at least one compressing stage.

With multi-stage compression it is known to 10 recool the compressing medium between separate stages in order to avoid on the one hand impermissible increases of temperature in the medium delivered and in the machine, and on the other hand to reduce the power required for compressing. According to known proposals the intermediate cooling is effected in such a way that an intermediate cooler of a size which will ensure the requested cooling effected is built on to the compressor, or, as a separate aggregate from the compressor, is inserted between each two stages of the compressor by means of pipes. It is then evident that the saving of space and weight obtained in any case with centrifugal compressors with high-stage pressure ratios is again cancelled to a large extent by adopting such separate intermediate coolers.

Also the known jacket-cooling adopted with slow-speed centrifugal compressors, which makes use of a double-walled compressor casing with hollow cooling spaces lying between them, cannot prove to be satisfactory in consequence of the surface being necessarily of modest dimensions for carrying away comparatively great quantities of heat, such as are produced in compressors with high and super-high stage-pressure ratios.

These draw-backs can be avoided with the present invention. As compared with the compressors mentioned with known form of coolers, the multi-stage compressor according to the invention can be built for the service much lighter, at less cost, and taking up less room. In order to give a comparison, it is mentioned that—assuming equal output and the same pressure ratio—the dimensions for a reciprocating compressor are 3 m. x 3 m. x 1 m., for a slow-speed radial compressor 1.8 m. x 1.2 m. x 1.2 m., and for a two-stage compressor according to the invention only 0.8 m. x 0.8 m. x 0.7 m. The last mentioned is particularly suitable for producing compressed air in workshops, steel works, mines, and also for the production of power gas and for building into gas turbine plants and also for compressing gases and vapours in chemical processes.

2

Examples of execution of the subject matter of the invention are illustrated by way of example in the accompanying drawing, where

Fig. 1 shows a first form of execution, in axial cross-section,

Fig. 2 a second form of execution in axial cross-section, and

Fig. 3 a view of the impeller with the casing-half removed, and partly in section on the line III—III of Fig. 2.

Fig. 4 is a section along line IV—IV of the compressor unit according to the invention illustrated in Fig. 2.

In the example of execution shown in Fig. 1, 15 the impeller body 1 is fitted with two impeller wheels 2, 2' carrying blades 3, 3' which have a radial extension in cross-section normal to the impeller axis 4 at least in the zones lying at some distance from the axis 4. In this way the blades 3, 3' are prevented from being subjected in these zones to additional bending stresses, subjected as they are to a considerable stressing from centrifugal forces, running at high peripheral speeds of, for instance 300 m./s. and more, as is necessary for the highest stage-pressure ratios of 1.5 and more, referred to atmospheric air. At both ends the impeller body 1 is carried in the bearing positions 5, and at one end is coupled to the driving shaft 6. The impeller body 1 is surrounded by a casing which consists of an inlet part 7, a deviating part or chamber 8 and an outlet spiral 9. In the deviating part 8 of the casing the annular-shaped intermediate cooler 10 surrounding the cone shaped impeller wheel 2' is built in and may consist for instance of a pipe coil conducting the cooling medium and surrounding the impeller wheel 2' of the second stage annularly, its beginning 16 and end 17 leading out of the compressor casing and being connected to supply and return piping for cooling medium (not shown in the drawing).

The medium delivered, for instance atmospheric air, is drawn-in in the direction of the arrow 11 and precompressed by the impeller blades 3 and the diffusor 12 following them. From the diffusor 12 the medium passes through the diverting part 8 and the intermediate cooler 10 in the direction of the arrow 13, and then flows through the impeller 2' and through the diffusor 14 into the spiral 9 and the delivery branch 15, from where it is led to the points of use.

By means of the intermediate cooler 10, the temperature of the medium flowing in to the second stage is reduced approximately to cooling-water temperature, whereby a reduction of the

volume of the medium to be compressed further is obtainable, and also directly proportional a reduction of the power required for the compression in the upper stage. At the same time the specific gravity of the medium handled is correspondingly increased, which causes an increase in the stage-pressure ratio in the upper stage.

According to Figs. 2 and 3 two pressure stages are provided on the double cone shaped impeller body 38 in such a way that each side of it is fitted with blades 39 and 39', which form the low-pressure and high-pressure stages respectively. These blades 39 and 39' extend in a screw-line form from the impeller inlet to the impeller outlet, in the direction of rotation opposite to the direction of rotation 18 of the propeller, and make at the outlet with the peripheral tangent 40 of the impeller 38 an angle α whose cosine is greater than the ratio of the velocity of flow between blade 39 and 39' to the doubled peripheral speed of the blades at the outlet. The impeller 38 is carried at both ends in the bearing positions 19 of the compressor casing 21 and coupled to the driving shaft 20. The part of the casing 21 surrounding the low-pressure part of the impeller 38 is made with double walls in such a way that the medium, drawn-in in the direction of the arrows 22 through the passages 23, lying between the blades 39, flows into the diffusor 24 and is diverted inwardly in the direction of the arrow 25 in the outer chamber 26 in the casing. From here, the medium passes into the inner hollow space 27 of the casing, from where the passages 28 formed by the walls of the diffusors 24 lead into the hollow space 29 of the part of the casing 21 surrounding the high-pressure part of the impeller 38. In the annular chamber 29 the medium is diverted in the direction of the arrow 33 and led to the high-pressure part of the compressor. It flows between the blades 39' and in the direction of the arrow 31 through the diffusor 30 into the spiral 32 and from there passes through the delivery branch 34 to the points of use.

The intermediate cooler, consisting for example of a pipe coil 35, is divided into two parts, one of which is located in the hollow space 26 of the first stage, and the other in the hollow space 29 of the second stage, the two parts surrounding the impeller body 38 annularly. The cooling medium is led to the pipe coil of the intermediate cooler 35 at the inlet position 36 and leaves it at the outlet position 37.

The tube coil forming the cooling surface in chamber 29 is illustrated in Fig. 4 of the drawings. It is made of semicircular tubes 41 and 41', the ends of which are rolled into plates 42 and 42', respectively, which plates are adjacent the flange plane 43 of the pressure casing 44. The individual tubes are interconnected to form a continuous coil upon assembly of the casing.

The compressors described above as two-stage compressors may, of course, be built also in the same sense with more than two stages, whereby, for instance, two compressors shown in Fig. 2 could be connected to a central gear which is driven by a single driving machine, so that each of the two compressor aggregates can be driven at the speed most favourable to it. Within the scope of the invention fall also other forms of execution in which a centrifugal compressor with one or more stages is connected, through a cooler built into it in accordance with the invention, to a further compressing stage, formed for instance as a reciprocating or rotary piston compressor. It would also be possible, making use of

the form of execution shown in Fig. 1, to provide 3 or more stages on one and the same impeller body and to provide them with intermediate cooling built as an organic unit together with the compressor.

I claim:

1. A multistage compressor comprising an impeller body having a cone shaped surface portion, vanes extending from said surface portion, a substantially cylindrical pressure casing surrounding said surface portion and forming an annular chamber of substantially triangular radial sectional configuration, and substantially annular cooling means disposed in said chamber and extending around the axis of rotation of said impeller body.

2. A multistage compressor as defined in claim 1, said cooling means consisting of tube spirals having the axis of rotation of said impeller body as a center.

3. A multistage compressor comprising an impeller body comprising a plurality of cone shaped surface portions, vanes extending from said surface portions, a substantially cylindrical pressure casing surrounding said surface portions and forming annular chambers of substantially triangular radial sectional configuration, and substantially annular cooling means disposed in said chambers and extending around the axis of rotation of said impeller body.

4. A multistage compressor comprising a double cone shaped impeller body in which the two cones have a common base area, vanes extending from both cone surfaces of said body, a pressure casing surrounding said body and forming annular chambers of substantially triangular radial sectional configuration, and substantially annular cooling means disposed in said chambers and extending around the axis of rotation of said impeller body.

5. A multistage compressor comprising a double cone shaped impeller body in which the two cones have a common base area, vanes extending from both cone surfaces of said body and forming compressing channels having outlet portions at the large diameter portion of said body, a pressure casing surrounding said body and forming annular chambers having inlet portions adjacent the large diameter portion of said body and being connected for compressed medium flow with the outlet portions of said channels, and having outlet portions adjacent the small diameter portions of said body, the outlet portion of one of said annular chambers being connected for compressed medium flow with the inlet portion of the other of said chambers, and substantially annular cooling means disposed in said chambers and extending around the axis of rotation of said impeller body.

6. A multistage compressor comprising a double cone shaped impeller body in which the two cones have a common base area, vanes extending from both cone surfaces of said body, cone shaped wall portions surrounding said body adjacent said vanes and forming therewith channels having outlet portions at the large diameter portion of said body, a pressure casing surrounding said body and forming annular chambers radially outside of said wall portions and having inlet portions adjacent the large diameter portion and outlet portions adjacent the small diameter portion of said body, a second cone shaped wall portion disposed inside one of said chambers and being spaced from and surrounding one of said first wall portions and form-

ing a conduit connected for compressed medium flow at its small diameter end with the outlet portion of the chamber in which it is placed and being connected for compressed medium flow at its large diameter end with the inlet portion of the other chamber, and substantially annular cooling means disposed in said chambers and extending around the axis of rotation of said impeller body.
